UNITED STATES PATENT OFFICE.

WARREN C. EVANS, OF EXETER, NEW HAMPSHIRE, AND EUGENE H. TAYLOR,
OF LYNN, MASSACHUSETTS, (SARAH M. EVANS ADMINISTRATRIX OF
SAID WARREN C. EVANS, DECEASED,) ASSIGNORS TO THE AUTOMATIC
HEEL TRIMMING AND BURNISHING MACHINE COMPANY, OF EXETER,
NEW HAMPSHIRE, A CORPORATION OF MAINE.

MEANS FOR SECURING TOOLS UPON SHAFTS.

No. 835,820.

Specification of Letters Patent.

Patented Nov. 13, 1906.

Application filed March 27, 1905. Serial No. 252,199.

To all whom it may concern:

Be it known that we, WARREN C. EVANS,
residing at Exeter, in the county of Rocking-
ham and State of New Hampshire, and Eu-
5 GENE H. TAYLOR, residing at Lynn, in the
county of Essex and State of Massachusetts,
citizens of the United States, have invented a
certain new and useful Improvement in
Means for Securing Scouring and other Ro-
10 tary Tools for Boots and Shoes upon Their
Shafts, of which the following is a specifica-
tion, reference being had therein to the accom-
panying drawings.

The invention relates to means for secur-
15 ing upon their supporting and operating
shafts scouring and other rotary tools which
are employed in the manufacture of boots and
shoes.

The invention consists in an improved
20 means for the said purpose which shall enable
the tool to be quickly and readily applied to
or removed from its shaft and by which the
rotation of the tool in unison with its shaft
shall be insured.

25 We have illustrated an embodiment of our
invention in the accompanying drawings, in
which latter—

Figure 1 shows in elevation a rotary scour-
ing-tool and its shaft with our invention ap-
plied thereto. Fig. 2 is a view mainly in sec-
30 tion on a vertical plane lengthwise of the
shaft.

We have illustrated the invention as em-
ployed for connecting a scouring-tool to its
35 shaft; but it is not necessarily restricted to
use in this particular connection.

Having reference to the drawings, 1 design-
ates the tool-shaft, and 2 a bearing therefor,
3 being a rotary scouring-tool having a hub
40 31, which fits upon the end of said tool-shaft
projecting beyond bearing 2. For the pur-
pose of securing the tool in place the said end
is furnished with a transversely-extending
pin or equivalent projection, as 100, which
45 when the tool is in working position upon the
shaft projects radially across the outer end of
the hub 31 of the tool. Thereby the tool is
held from accidentally coming off the end of
the shaft. In this instance the said pin is fixed
50 to the shaft. The interior of the hub of the
tool is formed with a longitudinal groove 32,

open at both ends, and in applying the tool to
the shaft the tool is held in position to pre-
sent the groove 32 to the pin 100. The tool
may now be slipped onto the shaft, the pin 55
passing through the groove. When the tool
is fully on, it is turned part way around, so
as to shift the groove away from the pin. So
long as the groove remains out of register with
the pin the latter will hold the tool on the shaft. 60

For the purpose of preventing unintended
relative movement between the tool and shaft
which would place the groove and pin in line
with each other and enable the tool to be-
come displaced on or from the shaft a latch 4 65
is provided. The said latch is pivoted at its
inner end at 41 within a transverse open
groove or slot 42, which is formed in the end
of the shaft 1 and is acted upon by a spring
43, operating to project its engaging edge at 70
the side of the shaft and cause said edge to
enter the groove 32 of the interior of the hub
of the tool. So long as the latch occupies the
groove 32 the tool will be held thereby from
turning relative to the shaft, and consequently 75
it will be held lodged by the pin 100 from end-
wise movement on the tool-shaft. Should,
however, the latch 4 be pressed inward by
hand, so as to withdraw it from the groove 32,
the tool may now be turned by hand relative 80
to the shaft, and by bringing the groove in ap-
position to the holding-pin the tool will be free
to be withdrawn from the tool-shaft. For
convenience in working the latch by hand for
the purpose of disengaging it from the groove 85
in the hub of the tool the free extremity of
the latch projects beyond the outer end of the
hub into readily-accessible position, and for
advantage in moving the latch against the
resistance of the spring the shaft is furnished 90
with a flattened extension which is parallel
with the outstanding portion of the latch.
Upon taking hold of the two projecting por-
tions between a thumb and one or more fin-
gers of one hand and applying force of com-
pression the latch will be caused to move in-
ward, and thus disengaged from the tool. 95

What we claim is—

1. In combination, a tool-shaft having one
extremity thereof adapted to receive a tool 100
and provided with a radial tool-locking pro-
jection, the tool having the open groove or slot

- to enable the tool to be slipped over the said projection onto the end of the tool-shaft, and a latch independent of said tool-locking projection, operating to lock said tool from rotary movement on said shaft with said groove or slot out of register with said projection.
2. In combination, a tool-shaft having one extremity thereof adapted to receive a tool, and provided with a radial tool-locking projection, the tool having the open groove or slot to enable the tool to be slipped over the said projection onto the end of the tool-shaft, and a latch carried by the said tool-shaft to enter said groove or slot and thereby lock said tool with the groove or slot out of register with the projection.
3. In combination, a tool-shaft having one extremity thereof adapted to receive a tool, and provided with a radial tool-locking projection, the tool having the open groove or slot to enable the tool to be slipped over the said projection onto the end of the tool-shaft, and the spring-actuated latch mounted on the tool-shaft and entering the said groove or slot to prevent the tool from turning to

place the groove or slot in register with the projection.

4. In combination, a tool-shaft having one extremity thereof adapted to receive a tool, and provided with a radial tool-locking projection, the tool having an open groove or slot to enable the tool to clear the projection in being slipped onto the tool-shaft, and the latch, entering the said groove or slot to lock the tool from turning, with the groove or slot thereof out of register with the projection, and provided with the operating extension projecting longitudinally beyond the tool.

In testimony whereof we affix our signatures in presence of witnesses.
